HOOK-BLOCK ASSEMBLY

Spencer W. Long, Inglewood, Calif., assignor, by mesne assignments, to Armco Steel Corporation, Middletown, Ohio, a corporation of Ohio

Filed Feb. 5, 1957, Ser. No. 638,267

1 Claim. (Cl. 254—192)

This invention relates to apparatus of the type used in the drilling of wells, and is particularly directed to improvements in a hook-block assembly. Devices of this type are used in the derrick or mast to support the load of the drill pipe or casing, and for other purposes. This invention relates to improvements over the construction disclosed in my prior Patent No. 2,661,232, granted December 1, 1953, for Drilling Hook Assembly.

It is an important object of this invention to provide an improved form of gimbal connection for supporting a spring hook from a traveling block. Such a device permits a close coupling of the traveling block and spring hook for minimum overall length, while at the same time permitting universal swiveling movement between the block and the hook. In this way the traveling block may cant slightly as it rises and falls in the derrick or mast without imparting this canting movement to the spring hook. Accordingly, the tendency for the lower end of the hook to swing from side to side as the block cant in one direction or the other is greatly reduced.

Another object of my invention is to provide an improved tongue construction for closing the hook opening. A tongue is provided with a bail-receiving notch surface which extends for the full width of the hook body. In this way, there are no sharp edges of the hook body or tongue presented to the bail of the swivel which is received in the notch. Accordingly, damage to the bail is prevented and deformation of close-fitting relatively movable parts of the body and tongue is avoided.

Other and more detailed objects and advantages will appear hereinafter.

In the drawings:

Figure 1 is a front elevation partly in section, showing a preferred embodiment of my invention.

Figure 2 is a sectional side elevation taken substantially on the lines 2—2 as shown in Figure 1.

Figure 3 is a perspective view of the tongue of the spring hook, shown on an enlarged scale.

Figure 4 is an enlarged transverse sectional view taken substantially on the lines 4—4 as shown in Figure 2.

Figure 5 is an enlarged transverse sectional view of the rotation lock assembly and adjoining parts taken substantially on the lines 5—5 as shown in Figure 2.

Figure 6 is a sectional view of the rotation lock assembly taken substantially on the lines 6—6 as shown in Figure 5, the parts being in locking position.

Figure 7 is a sectional view similar to Figure 6, the parts being in retracted position.

Figure 8 is an end view of the left hand end of Figure 5.

Figure 9 is an end view of the right hand end of Figure 5.

Referring to the drawings, the traveling block generally designated 10 includes a pair of side plates 11 and 12 supporting a stationary shaft 13 which extends between them. A plurality of cable sheaves 14 are each rotatably mounted on the shaft 13 by means of suitable bearings (not shown). A cap 15 extends between the upper ends

2

of the plates 11 and 12 and is held in place by means of a bolt 16. Similarly a spacer 17 extends between the side plates 11 and 12 at a location below the sheaves 14 and this spacer is held in place by means of bolts 18. 5 Cable guards 19 may be detachably connected to the cap 15 and spacer 17.

The spring hook generally designated 20 is connected to the traveling block 10 by means of an improved form of gimbal connection 21 embodying my invention. 10 The member 22 has a pair of oppositely extending coaxial trunnions 23 which project from faces 22a and 22b which abut the inner surfaces of the side plates 11 and 12. These trunnions 23 are received within aligned bushings 24 provided in side plates 11 and 12 below the lower extremities of the sheaves 14. The member 22 carries a headed cross pin 25 which has an axis which intersects the axis of the trunnions 23 at right angles. The load-carrying shank 26 of the hook assembly 20 has an eye portion 27 on its upper end which is supported on the pin 25. The eye portion 27 extends into a recess 28 provided in the member 22. A bushing 29 may be provided within the eye for contacting the pin 25. A nut 30 holds the pin 25 in position and a key 22a welded to member 22 prevents it from turning. The trunnions 23 and the cross pin 25, in effect provide gimbals permitting the shank 26 to have universal movement with respect to the traveling block 10.

The spring hook 20 has a nut 31 threaded to the lower end of the shank 26 and a bearing assembly 32 is supported on this nut 31. The lower ends of the compression springs 33 and 34 are supported on bearing assembly 32. The upper ends of these springs engage the shoulder 35 on the housing 36. When the springs are compressed, shoulder 37 on housing 36 rests on bearing assembly 32. A skirt 38 shrunk on the shank 26 encloses the upper end of the housing 36 in telescopic relationship. The main hook body 39 is connected to the housing 36 by threads 40. A recess 41 is formed in the hook body 39 to provide clearance for the nut 31. 40 A rotation lock ring 42 is rotatably held between housing 36 and body 39 and has a slid able connection with the axial keyway 43 formed on the outer surface of the nut 31. Recesses 44 are provided in the under surface of the ring 42 and these recesses are adapted to be 45 engaged by a locking pawl 65, as described below, for the purpose of preventing rotation between the hook body 39 and the shank 26. A bar 45 acts as a key to prevent unscrewing of the nut 31 with respect to the shank 26.

Side notches 46 are provided on the hook body 39 for 50 the purpose of supporting the elevator links (not shown), as will be readily understood by those skilled in the art. The side notches 46 may be closed by means of the links 47 to retain the elevator links in place. The main load supporting notch 48 in the hook body 39 is closed by 55 means of the tongue 49 which is pivotally connected to the hook body 39 by means of the pivot pin 50. The pivot pin 50 passes through the bore 51 in the tongue 49.

The tongue 49 has a relatively narrow central section 52 which is received within a cooperating groove 53 60 formed on the hook body 39. The tongue has a relatively wide crowned surface 54 in the form of a double curved saddle for reception of the swivel bail (not shown). This saddle surface 54 is convex in the central vertical plane parallel to the axis of pin 50 and concave in the 65 central vertical plane normal to the axis of the pin 50. It extends for the full width of the hook bill 55 (see Figure 1). The swivel bail thus rests on a continuous uninterrupted surface which is free of sharp edges and projections. The load imposed by the swivel bail on the tongue 49 maintains the tongue 49 in closed position as 70 shown in Figure 2.

A releasable latch may be provided to prevent opening movement of the tongue 49 about the pivot pin 50 and

as shown in Figure 2 this means may include the pivoted latch 56 engaged by the spring-urged plunger 57. An element on the latch 56 engages the shoulder 58 on the hook body 39 to prevent opening movement of the tongue. Upon release of the latch 56, the tongue 49 ⁵ may be swung to the phantom line position shown in Figure 2, the abutment 49a limiting the extent of opening movement.

The rotation lock assembly shown in Figures 5 to 9 inclusive comprises a cage 60 which is axially insertable ¹⁰ into a stepped bore 61 provided in the hook body 39. This cage 60 carries a latch shaft 62 and a pawl shaft 63, each of which is mounted to turn in the cage 60. A nut 64 holds the cage 60 in position against disassembly.

A pawl 65 is fixed on the pawl shaft 63 and this pawl is adapted to engage the recesses 44 in the lock ring 42. A torsion spring 66 acts to turn the pawl shaft 63 in a direction to extend the pawl 65. A pawl operating lever 67 is fixed on one end of the pawl shaft 63 in order to retract the pawl 65 against the action of the torsion spring 66. A torsion spring 68 acts on the latch shaft 62 to turn it in a clockwise direction as viewed in Figures 6 and 7. A latch 69 fixed on the shaft 62 is adapted to engage an abutment 70 formed on the pawl 65. A latch operating lever 71 is fixed on the projecting end of the latch shaft 62. Actuation of the lever 71 serves to turn the latching shaft 62 in a counterclockwise direction as viewed in Figures 6 and 7.

From the description, it will be understood that actuation of the lever 67 serves to turn the pawl shaft 63 in a direction to retract the pawl 65 from the position shown in Figure 6 to the position shown in Figure 7. The spring 68 then moves the latch 69 into position to engage the shoulder 70 on the pawl 65. This serves to latch the pawl 65 in retracted position. The hook body 39 is then free to turn with respect to the shank 26. Actuation of the lever 71 moves the latch 69 out of the path of movement of the shoulder 70 with the result that the spring 66 swings the pawl 65 into the extended position shown in Figure 6 to engage one of the recesses 44 of the lock ring 42.

Having fully described my invention, it is to be understood that I do not wish to be limited to the details herein set forth, but my invention is of the full scope of the appended claim.

I claim:

In a hook-block assembly, the combination of: a traveling block having parallel side plates defining the side boundaries of said block, a plurality of sheaves rotatably supported between said plates, said plates projecting below the lower portions of said sheaves and being provided with aligned apertures, a member positioned between the lower ends of said plates and having faces abutting the inner surfaces of said plates, said member having a pair of coaxial oppositely extending horizontal trunnions projecting from said faces and pivotally mounted in said apertures, said member having a central recess, a spring hook assembly having a housing positioned below the said member and having a hook element fixed thereto, said housing being larger than the recess in said member, a load carrying shank within said housing and extending upwardly into said recess, said shank having a transverse opening, a horizontal cross pin mounted upon said member and extending through said transverse opening to pivotally support said shank, and means including a spring within the housing and encircling said shank for supporting the housing upon said shank.
